[57] CLAIM

The ornamental design for a massage bench, as shown and described.

DESCRIPTION

FIG. 1 is an enlarged fragmentary left side perspective view of a massage bench, of our new design, showing the hand and arm support portion;

FIG. 2 is another perspective view thereof, showing the foot end portion of the massage bench;

FIG. 3 is an end elevational view of the head portion;

FIG. 4 is an end elevational view of the foot portion;

FIG. 5 is a side elevational view;

FIG. 6 is a top perspective view;

FIG. 7 is a top plan view; and,

FIG. 8 is a bottom plan view.
